UNITED STATES PATENT OFFICE.

GEORGE B. HURD, OF NEW YORK, N. Y.

DESIGN FOR A STATIONERY-BOX.

SPECIFICATION forming part of Design No. 31,627, dated October 10, 1899.

Application filed June 20, 1899. Serial No. 731,349. Term of patent 14 years.

To all whom it may concern:

Be it known that I, GEORGE B. HURD, a citizen of the United States, residing at New York, Manhattan borough, in the county of New York and State of New York, have invented and produced a new and useful Design for Stationery-Boxes, of which the following is a specification.

Reference being had to the accompanying drawings, forming part hereof, Figure 1 is a perspective view of my box, and Fig. 2 is a top plan view of the same.

As shown in the drawings, the box, which is intended to contain writing-paper and envelopes, is of oblong shape over all, its lines being rectangular. In the interior of the box, midway between its two side walls and resting upon the base, is a raised portion forming a hump and having the vertical walls A A' and top plane surface B, the latter being parallel with but lying in a lower plane than the peripheral edge of the main wall of the box, as

seen. The plane surface B and the side walls A A' are sufficiently long to extend entirely across the box, as shown in Fig. 2. Rectangular spaces C and D are comprised, respectively, between the wall A and the main wall of the box, and between the wall A' and the main wall of the box, and a shallow rectangular space E is formed between the plane surface B and the top of the box.

Having described my invention, what I claim as new, and desire to secure Letters Patent, is—

The design for a stationery-box, as herein shown and described.

In testimony whereof I have hereunto set my hand in the presence of two subscribing witnesses.

GEORGE B. HURD.
